UNITED STATES PATENT OFFICE.

HORACE GROFF, OF WILMINGTON, DELAWARE.

COIN-COUNTING DEVICE.

1,400,053.

Specification of Letters Patent. Patented Dec. 13, 1921.

Application filed December 24, 1919. Serial No. 347,177.

To all whom it may concern:

Be it known that I, HORACE GROFF, a citizen of the United States, residing at Wilmington, New Castle county, State of Delaware, have invented a certain new and useful Improvement in Coin-Counting Devices, of which the following is a full, clear, and exact description.

My invention relates to improvements in coin counting devices and has for its object to provide a simple apparatus for counting coins.

It further has for its object to provide an apparatus which enables the rapid examination of coins to detect the presence of any imperfect or foreign coins or counters.

The following is a description of an embodiment of my invention, reference being had to the accompanying drawings in which,

Figure 1 shows a plan view of my apparatus;

Fig. 2 shows a front elevation of the same partly in section;

Fig. 3 shows a section on the line 3—3, Fig. 2;

Fig. 4 shows a similar section with the parts in different position;

Fig. 5 shows a detailed section through the distributing device; and,

Fig. 6 shows the distributing device in perspective.

Referring more particularly to the drawings, 1 is a hollow base having hinged thereto adjacent to its upper edge a dumping plate 2, normally held in horizontal position by a spring 3 and from which when depressed coins are adapted to slide into a receiving and discharging trough 4 supported by the base. Upon the upper surface of the base is a grille 5 preferably composed of metallic side bars 6 connected by cross-bars 7, the cross-bars being spaced apart so as to provide spaces or traps having openings of approximately the size of the coins 8 to be counted. The extremities of the grille are provided with platforms 9—9 over which the distributor hereinafter referred to rests at the end of each reciprocation. 10 is the distributor, the same consisting of a tubular member flaring at both top and bottom and of a diameter sufficient to receive the coins to be counted so that they will easily pass therethrough, the diameter of the body portion being slightly larger than the diameter of the coins and approximately the same as

the distance between the cross-bars 7. This distributor is provided with lateral extensions 11, which fit in grooved bars 12 carried by the base so that the distributor 10 can slide thereon from one end of the structure to the other. Pivotaly mounted in the base at each end is a U-shaped lever 13 which is connected by a link 14 with the end of the dumping plate 2. The lever 13 is inclined downwardly, as shown so that when the distributor 10 comes, in contact therewith and is still further moved it depresses the lever 13, thereby acting through the link 14 to depress the dumping plate 2 so as to dump any coins which may be resting upon the plate into the chute 4, from which they discharge at the lower end.

In operating this device the coins to be counted are placed within the distributor 10, said distributor being at that time upon one of the platforms 9. The distributor 10 is then moved to the other platform, resulting in the depositing of a coin in each of the spaces between the bars 7. These coins are thus exposed to view and if there are ten spaces it is evident that ten coins have been discharged to the dumping plate. After they have been examined, which for an experienced person takes but a moment of time, the distributor 10 is moved still farther in the same direction until it engages the spring 13 at that end, causing the plate to dump and discharging the coins into the chute or trough. Thereupon the distributor is moved in the other direction until it reaches the other platform 9, where it is halted until the examination of the coins deposited on the plate has been made, whereupon it is still further moved so as to dump the plate in the manner before described. In this way a large number of coins can be quickly counted and examined in a short time, thus expediting the work to be done. This device can be made of various sizes and the height and diameter of the distributor can be varied so that devices can be adapted for coins of different sizes and for different capacities. The coins to be counted are supposed to be of the same denomination and can be fed to the distributor by any suitable means. The coins are caught in the trap openings formed by the grille, the forward edge of the coin dropping therein and the coin being pushed along until it falls entirely within the opening. The flaring

lower end of the distributor aids in the depositing of the coins in the traps, since it permits a more free dropping of the lower coin. The bars in the grille are of such a thickness, vertically, that when a coin is in a trap the bars are out of contact with the next succeeding coin within the distributor.

If any false or defective coins are replaced, the coins can be counted by keeping track mentally or mechanically of the number of reciprocations of the distributor.

As will be evident to those skilled in the art, my invention permits of various modifications without departing from the spirit thereof or the scope of the appended claims.

What I claim is:

1. In a coin counting device, the combination of a base, a dumping plate supported thereby, a coin trap having a series of openings located above said dumping plate, a distributor adapted to receive coins and slide over said openings, means for guiding said distributor, and means lying in the path of said distributor and adapted to be engaged thereby and automatically actuated by said distributor when it passes said series of openings so as to dump said plate.

2. In a coin counting device, the combination of a base, a dumping plate supported thereby, a coin trap having a series of openings located above said dumping plate, a distributor adapted to receive coins and slide over said openings, means for guiding said distributor, means lying in the path of said

distributor and adapted to be engaged thereby and automatically actuated by said distributor when it passes said series of openings so as to dump said plate, and similar means for dumping said plate situated at the other end.

3. In a coin counting device, the combination of a base, a dumping plate supported thereby, a coin trap having a series of openings located above said dumping plate, a distributor adapted to receive coins and slide over said openings, means for guiding said distributor, and means comprising a lever extending into the path of said distributor and adapted to be engaged thereby and automatically operated by said distributor when it passes said series of openings so as to dump said plate.

4. In a coin counting device, the combination of a base, a dumping plate supported thereby and pivoted thereto, a spring normally holding said plate in horizontal position, a coin trap having a series of openings located above said dumping plate, a distributor adapted to receive coins and slide over said openings, means for guiding said distributor, a downwardly pointing lever pivoted to said base and connected to said dumping plate so that when said lever is depressed it tilts said dumping plate, the lower end of said lever lying in the path of said distributor and being engaged so as to be depressed thereby when said distributor passes said series of openings.

HORACE GROFF.
